UNITED STATES PATENT OFFICE.

VICTOR H. SLINACK, OF PHILADELPHIA, PENNSYLVANIA, ASSIGNOR TO PENNSYLVANIA GLOBE GAS LIGHT COMPANY, OF PHILADELPHIA, PENNSYLVANIA, A CORPORATION OF PENNSYLVANIA.

BURNER FOR INCANDESCENT MANTLES.

SPECIFICATION forming part of Letters Patent No. 764,155, dated July 5, 1904.

Application filed March 5, 1903. Serial No. 146,275. (No model.)

To all whom it may concern:

Be it known that I, VICTOR H. SLINACK, a citizen of the United States, residing at the city of Philadelphia, in the county of Philadelphia and State of Pennsylvania, have invented 5 certain new and useful Improvements in Burners for Incandescent Mantles, of which the following is a specification.

One object of the present invention is to 10 provide a burner which shall effect and consume or burn a mixture of air and gas in those proportions and relations which give a substantially maximum heating power, and therefore in connection with an incandescent 15 element a high lighting efficiency.

Another object of the invention is to provide improved means for regulating the mixture of air and gas.

Other objects of the invention are to provide 20 features of construction which benefit the operation of the burner.

To these and other ends hereinafter set forth the invention, stated in general terms, comprises the improvements to be presently 25 described and finally claimed.

The nature, characteristic features, and scope of my invention will be more fully understood from the following description, taken in connection with the accompanying drawings, forming part hereof, and in which— 30

Figure 1 is a central sectional view of a burner embodying features of the invention. Fig. 2 is a top or plan view of the same. Fig 3 is a side elevational view, drawn to a reduced scale, of the burner. Fig. 4 is a view of the under side of the burner-head, and Fig. 5 is a top view of the shank of the burner-head.

In the drawings, 1 is a tubular burner-head. It is shown as somewhat larger in diameter at its base than it is at its top.

2 is a toothed disk arranged at the outlet of the burner-head with the points of its teeth in contact with the inner rim thereof.

3 is a downwardly-tapering guide arranged beneath the toothed disk.

4 is a truncated hollow pyramid arranged

between the guide 3 and the inlet portion of the burner-head and having its side walls reversely curved or warped, as at 5 and 6, and 50 provided with a series of slots 7, extending continuously from its top to its base.

As shown, the disk and the guide are made of separate pieces and are held together by a screw 8, whose head engages the truncated 55 pyramid 4.

The shank 9 of the burner-head is tubular and of considerably less diameter than the burner-head. At its top it is shown as flaring outward and as provided with a notched 60 flange 10, Fig. 5, which by a movement of rotation is engaged by or disengaged from projections 11, Fig. 4, on the burner-head, so that the head and shank may be connected or disconnected. 65

12 is an air and gas mixing tube, having openings 13 in its base, which latter is shown as of larger diameter than the rest of the tube.

14 is a regulator or screw arranged radially and so as to project into the tube 12. As 70 shown, it can be caused to extend clear across the tube 12, and it is, generally speaking, located about midway of the height of the burner and as shown. The tube 9 is slotted, as at 15, so as to accommodate the screw 14 75 and permit of the removal of the superstructure from the gas and air mixing tube 12. This slot also prevents rotation of the head of the burner, which would be undesirable for reasons that are well understood and among 80 which mention may be made of the fact that it is common practice to align the side support for the mantle with parts of a lantern in order to avoid a multiplicity of shadows. 85

16 is a sleeve rotatably mounted on the mixing-tube and provided with slots, which may be caused to correspond more or less with the slots 13 and in that way regulate the effective size of the latter, and consequently the amount of air-admission space afforded 90 thereby.

17 is a perforated guard of larger diameter than the sleeve, and 18 represents means for supplying a jet of gas.

19 is a gallery carried by the burner-head and provided with means 20 for holding a mantle-support.

In operation the warped shape of the wall of the pyramid 4 imparts to it such stiffness and strength that the slots 7 may be cut from its base to its top, and this is advantageous, because it affords free passage for the mixture of gas and air, and since these slots 7 are in alinement with the spaces between the teeth of the disk 2 the mixture of air and gas is thoroughly effected and freely delivered to be burned. The mixture is supplied to the flame broken up by passing between the teeth of the disk 2, and this imparts steadiness to the flame. The guide 3 serves to direct the mixture through the openings between the teeth. By adjusting the screw 14 the mixture can be regulated, because the more of the screw that projects into the tube the more is the velocity of the mixture retarded, and since the supply of gas is constant the supply of air is diminished, and by causing less of the screw 14 to project into the tube the velocity of the mixture is increased and more air is taken in. The fact that the guard 17 is of larger diameter than the air-mixing tube gives it such a large surface that the sum of the area of all the holes in it is substantially equal to or not less than the area of the openings 13. Thus there is an ample supply of air through the holes in the guard. Furthermore, the described burner by reason of its construction and the relative arrangement of its parts produces a mixture of air and gas and burns the same under conditions calculated to develop the maximum heat possible with the gas supplied, so that with an incandescent element excellent lighting results are effected.

40 It will be obvious to those skilled in the art to which my invention appertains that modifications may be made in details without de-

parting from the spirit thereof. Hence I do not limit myself to the precise construction and arrangement of parts hereinabove set forth, and illustrated in the accompanying drawings; but,

Having thus described the nature and objects of my invention, what I claim as new, and desire to secure by Letters Patent, is—

1. A burner comprising a tubular burner-head, a toothed disk arranged at the outlet of the burner-head with the points of its teeth in contact with the rim thereof, a downwardly-tapering guide arranged beneath the disk, a truncated hollow pyramid arranged between the guide and the inlet portion of the head and having its side walls reversely curved or warped and provided with slots extending continuously from its top to its base, and a gas and air mixing tube arranged to discharge into the open end of the pyramid, substantially as described.

2. A burner comprising a burner-head having a detachable shank, a notched flange and complementary projections between the head and shank, a toothed disk arranged at the outlet of the head, a truncated hollow pyramid arranged between the disk and the inlet portion of the head and provided with slots extending continuously from its top to its base, and a gas and air mixing tube penetrating said shank, substantially as described.

3. In a burner the combination of the cylindrical unobstructed air and gas mixing tube with an endwise-adjustable regulator narrower than the bore of the tube and arranged radially of the same, substantially as described.

In testimony whereof I have hereunto signed my name.

VICTOR H. SLINACK.
